[57] **CLAIM**

The ornamental design for a bridge assembly for stringed musical instruments, as shown and described.

DESCRIPTION

FIG. 1 is a front, top and right side perspective view of a bridge assembly for stringed musical instruments showing my new design;

FIG. 2 is a left side elevational view;

FIG. 3 is a rear elevational view; and

FIG. 4 is a bottom plan view.

In FIG. 1 the screw threads, which would be seen on the shafts between the drums and the baseplate, are omitted and, in front of the drums, are shown schematically, for convenience of illustration.

In FIG. 3 the structure which would be seen through the holes in the rear of the baseplate has also been omitted for convenience of illustration.
